UNITED STATES PATENT OFFICE

2,442,012

METHOD OF AND APPARATUS FOR
SCOURING WOOL

Bryan Leonard, Pembroke, Mass.

Application April 17, 1945, Serial No. 588,849

7 Claims. (Cl. 8—156)

1

The time-honored apparatus for scouring wool comprises a series of "bowls" or long tanks, each containing a bath of scouring liquid. Each bowl is equipped with a false bottom consisting of a screen located horizontally below the surface of the bath, and also with rakes which are operated mechanically to advance or feed the wool slowly toward its delivery end. At the latter end the wool is fed between squeeze rolls and from there it drops into the next bowl ahead of it in the series. At the last tank in the line the squeeze rolls deliver the wool to a conveyor which carries it through a drying mechanism.

Apparatus of this type has been in use for a great many years and it is still the equipment commonly used in most, if not all, of the larger wool scouring plants.

The present invention aims to improve both the methods of, and the apparatus for, scouring wool, with a view to increasing the efficiency of the prior art processes and mechanisms, and correspondingly reducing the expense of the scouring operation.

The nature of the invention will be readily understood from the following description when read in connection with the accompanying drawings, and the novel features will be particularly pointed out in the appended claims.

In the drawings,

Fig. 1 is a plan view of a scouring apparatus or mechanism constructed in accordance with this invention;

Fig. 2 is a vertical, sectional view taken substantially on the line 2—2, Fig. 1; and

Fig. 3 is a section on about the line 3—3 of Fig. 2.

According to the method provided by this invention, the wool is floated in a scouring liquid in a bowl, and while it is floating it is propelled by directing jets or sprays of scouring liquid against it at such an angle as to move it in the desired direction. It is moved through the bowl in this manner, then passed between squeeze rolls, and these operations are repeated in subsequent bowls until the desired degree of scouring has been attained.

I have discovered that this method of handling the wool and directing the scouring liquid against it, results in a surprising reduction in the length of time required to complete the scouring operation. The fact that the wool is suspended in a liquid medium so that it is free to open in all directions and can move freely under the impact of the spray, apparently is responsible for this result. Under these conditions the scouring solution penetrates far more readily into the mass of wool than by the orthodox methods. The strong jets or sprays striking the matted masses of wool, which are more or less bonded together with manure and other foreign

2

materials, open these masses quickly, increases the rate of separation of the heavy waste materials from the wool, and promotes the penetration of the scouring solution into both these materials and the fiber itself. The result is an increase in the amount of work performed by the solution in a given time, with a consequent reduction in the total period necessary for the scouring operation, and a reduction in the space required for the completion of this process.

The novel mechanism shown in the drawings for practicing this method comprises a bowl or tank 2 which may, for example, be in the neighborhood of twelve feet long and made in much the same manner as are the conventional bowls. It is provided with dirt collecting pockets 3—3, each of an inverted pyramidal form of rectangular cross-section in which the solids settle out and collect. Also supported in the bowl below the liquid level is the usual perforated false bottom or screen 4 which runs the greater part of the length of the tank. This may consist of wire mesh but, more commonly, is a perforated metal plate.

Wool is delivered to this bowl either directly from an opening machine or through a mechanical feeder, as desired. Usually the opening room is located above the scouring room and the wool is fed to the bowls by gravity through chutes, such as that indicated rather diagrammatically at 5 in Fig. 2. The scouring liquid is maintained at an approximately constant level, about as indicated in Fig. 2, and the locks of wool, after entering the bowl, are acted upon immediately by a rotating immersion wheel 6 having blades which force the wool downwardly into the bath, the roll also serving to give the wool an initial forward feeding movement that brings it into the range of the spraying apparatus.

This apparatus comprises several spray pipes 7 extending entirely across the bowl from one side thereof to the other, all connected to a common header 8 located at one side of the machine. The scouring liquid is forced through these pipes by a centrifugal pump 10 driven by an electric motor 11, preferably of the variable speed type. A valve 12 is included in the riser from the pump to the header 8 for controlling the volume of flow. While any suitable form of spray nozzle 50 can be used in the pipes 7, one that has provided very satisfactory consists simply of a curved tapered plate 13, secured fast on the pipe, the latter having a hole through it under the plate at such an angle that the liquid, issuing from it under considerable pressure, strikes the plate 13 and the latter breaks it up into a wide, well dispersed spray.

These pipes 7 are connected to the header 8 through slip joint unions, or equivalent connections, so that the angle at which the spray

strikes the surface of the scouring liquid and the wool floating on it, can be adjusted at will simply by turning the pipe around its own axis. Usually the nozzles of the extreme left-hand pipe 7 are adjusted at a steeper angle, or one more nearly vertical to the surface of the bath, than are the others, so that as the locks of wool come under the first line of jets, they are momentarily driven down substantially to the screen 4. However, this spray imparts some forward component of motion to the wool, and the others are directed less steeply so that as the floating wool passes into the range of successive lines of jets or sprays, it is propelled by them through the bowl.

When the wool reaches the delivery end of the bowl it comes into contact with the surface of a transferring roll 14 which is revolved slowly in a clockwise direction, Fig. 2. It has a peripheral surface consisting of a perforated plate or screen so that the scouring liquid can flow freely through it, but it is mounted in, and partially encircled by, an imperforate shell or casing 15, the left-hand edge of which is slightly below the surface level of the bath, but the opposite edge is above said level. A perforated pipe 16 extends through this roll and conducts scouring liquid from it through pipe connections 17 which deliver it into the supplemental tank 18. The rate of discharge is such that the liquid level in the roll is slightly lower than that outside of it, so that there is an inflow at the left-hand side, Fig. 2, of the roll. This flow cooperates with the action of the preceding line of sprays to carry the wool against the surface of the roll where it adheres to said surface and is lifted by it out of the bath and is deposited on an inclined vibrating feed plate 20. This member transfers the wool to the bite of a pair of squeeze rolls 21 and 22 which take out a high percentage of water from the fiber. Then it drops on to a belt conveyor 23 which delivers it to the intake end of the next bowl 24. Or, if the bowl 2 is the last of the series, then the conveyor 23 delivers the wool to the drying conveyor.

The particular squeeze roll mechanism shown is one manufactured and sold by Proctor & Schwartz of Philadelphia, and need not be described because any other suitable form of squeeze roll mechanism can be substituted for it. It is driven by an electric motor 25, either of the variable speed type, or else through a variable speed mechanism, so that the speed of rotation of the squeeze rolls can be adjusted, as desired. Also, sprocket and chain connections 26, Fig. 1, from the squeeze roll shaft to the transfer roll 14, drive the latter. Suitable connections can also be made to operate the vibrating mechanism for the feed plate 20 from this same motor.

At the delivery end of the bowl a weir 27, Fig. 2, is provided, this weir being adjustable to control the level of the liquid in the bowl. Any liquid flowing over the weir drops on to the apron 29 and flows into the supplemental tank 18. From the latter it may either be carried through pipe connections, partly shown at 28, to the counter-flow pump (not shown) through piping (not shown) and is returned in to the bowl 2 through a perforated pipe 40, or to another bowl. Or it may be handled in any other desired manner.

While the fluid fed to the spray pipes 7 may be clean liquid taken from a fresh source of supply, it is usually found preferable to re-circulate liquid taken from the bowl 2 itself through the spraying apparatus. For this purpose a screen box 34, Fig. 1, in which the intake and outlet sections are separated by a vertical screen 35, is positioned be-

side the bowl 2. Leading into the bottom of the intake section of this box is a pipe 39 which extends across the bowl below the screen 4, as shown in Fig. 2, the pipe being perforated on its lower side so that liquid from the bowl can flow freely into it and will be delivered by it to the screen box. The liquid flowing through the screen is conducted by a pipe 36, extending across and underneath the bowl, to the intake side of the pump 10 where it is forced into the spray pipe. A steam inlet pipe 38, Fig. 1, may be connected in to the pipe 36, if desired, to supply heat to the liquid before it goes to the nozzles.

The immersion roll 6 is driven by its own motor 15 through a variable speed mechanism 32 and belt connections to the shaft 33 of this roll.

The dirt collecting pockets 3-3, and that at the bottom of the supplemental tank 18, are equipped with dump valves 37, connected with hand levers 38, by means of which they may be operated at intervals.

As above stated, several of these bowls are customarily arranged end to end in a series or train. In the conventional systems used heretofore it has been common to employ five or six long bowls, all connected together so that the wool treated in one is transferred to the next one in front of it. In the last bowl it is a common practice in commission scouring to use a bleaching solution, and in that immediately preceding it the rinsing operation usually is performed. Also, in the customary arrangement fresh water is added continuously to the rinsing bowl, and all of the bowls are connected together by pipes in such a manner that the overflow from one is delivered to the bowl next behind it, but the overflow from the first bowl in the series is centrifuged and may or may not be returned to this or any other bowl. This arrangement maintains substantially the same liquid level in all the bowls, and it is employed with bowls operated in accordance with the present invention, but such an arrangement has not been illustrated because it is common in this art. With the present arrangement, in which the drip from the squeeze rolls is collected in the supplemental tank 18, it is preferable to provide a single pump (not shown) to take the overflow from the preceding bowl in the line, together with that from the tank 18 and to force it into the next bowl behind it at 40, Fig. 1. This is true as to all scouring bowls except the first one in the series, that is, the one in which the wool is initially delivered for scouring. That bowl, also, is equipped with a head box 30, but it receives the overflow from its own bowl, and the pipe connections leading from it conduct such overflow to the grease tank where it later is centrifuged or otherwise treated to recover the grease.

It should also be understood that the temperature of the baths in the several bowls should be carefully controlled, a temperature of 135° F. being about as high as it is safe to use. With the present arrangement, however, it has been found that the temperature can be lowered to 120° F. or less, while producing even better results than those obtained in prior art apparatus.

The pressure carried in the spray pipes can be adjusted by the control valve 12 and by the variable speed drive for the pump 10 to suit the requirements of the particular grade of wool being treated. A pressure of between five and twenty pounds has proved to be satisfactory. Usually a pressure of ten pounds is ample with nozzle openings one-quarter of an inch in diameter in an inch and a half nozzle pipe.

Important advantages of this invention are:

(1) The wool is opened much more rapidly, and a far more complete separation of the dirt and grease from it is produced in the first bowl than has been possible heretofore. And this result can be accomplished with a proportion of alkali and soap in the scouring liquor considerably lower than has been customarily used. This early separation of the heavy foreign material, particularly the dung and urine, is valuable in preventing the discoloration of the wool which otherwise would be produced by these materials. They naturally tend to dye the wool in the same way that butternut dyes were used in colonial times.

(2) It affords complete control of the work done at every stage of the process. This control is provided partly by the fact that all of the elements which affect the rate of movement of the wool through the apparatus are under control. And this applies not only to the mechanically driven elements, but also to the jets or sprays because the number used, the amount of liquid pumped through them, the pressure maintained on them, and the angle at which they operate, are all adjustable.

(3) A much quicker and deeper penetration of the scouring material into the fiber is obtained early in the process. This action assists the subsequent squeezing step in eliminating impurities before the wool is transferred to the next succeeding step.

(4) The scouring apparatus is much simplified from a mechanical standpoint. This, in turn, reduces installation and maintenance expenses as it eliminates the usual rakes, cams, gears, etc.

(5) The over-all efficiency of the installation is greatly improved. At least a 50% increase in production can be realized from a single train or series of these bowls, even with a shorter length of train than with the conventional system.

While I have herein shown and described a preferred form of apparatus for practicing the method provided by this invention, it will be evident that the invention is not limited to embodiment in the particular form shown. For example, the transfer of the wool from the range of operation of the spraying apparatus to the squeeze rolls in any individual bowl, may be performed in other ways. Some scourers may prefer to use a crab rake mechanism like that now in common use in scouring bowls to accomplish this transferring operation. These and other modifications may be made without departing from the spirit or scope of the invention.

While this invention has been directed primarily to the solution of problems arising in connection with the scouring of wool, it has also been found that the same method and apparatus can be used very advantageously in the operations of carbonizing, neutralizing, and otherwise treating wool in liquid agents. Also, the invention is equally useful in treating other textile fibers which will float and are of such length that they can be handled in essentially the same manner as wool. The scouring operation with which this invention was initially concerned is fundamentally one of cleaning in a liquid agent. But the same is true of scouring and bleaching cotton and performing similar operations, but perhaps with different liquids, on other textile fibers. Accordingly, the term "wool," as hereinafter used in the claims, should be understood to include these other fibers which can be handled by the method of this invention and in apparatus con-

structed in accordance with this invention. Also, the liquid agents used in operating on these other fibers should be understood to be the equivalent of the scouring liquid called for by the claims.

5 Having thus described my invention, what I desire to claim as new is:

1. That improvement in methods of scouring wool, comprising the steps of floating the wool in a bath of scouring liquid under such conditions

10 that the dirt can settle freely out of the upper part of said bath, propelling the wool through said bath by directing a series of well-dispersed sprays of such liquid against it from a series of points above the level of said bath and at such

15 an angle as to force the wool in the desired direction and to subject the wool to a scouring action, the wool floating freely except as the action of said sprays may momentarily submerge it.

2. That improvement in methods of scouring

20 wool, comprising the steps of floating the wool in a bath of scouring liquid under such conditions that the dirt can settle freely out of the upper part of said bath, propelling the wool through said bath by directing a series of well-dispersed

25 sprays of such liquid against it from points above a series of the level of said bath and at such an angle as to force the wool in the desired direction, and to subject the wool to a scouring action, the wool floating freely except as the action of said

30 sprays may momentarily submerge it, squeezing the scouring liquid out of the wool, and repeating these steps until the scouring operation has proceeded to the desired point.

3. That improvement in methods of scouring

35 wool, comprising the steps of floating the wool in a bath of scouring liquid under such conditions that the dirt can settle freely out of the upper part of said bath, propelling the wool through said bath by directing a series of well-dispersed

40 sprays of such scouring liquid against it from a series of points above the surface of said bath and at such an angle as to force the wool in the desired direction, and to subject the wool to a scouring action, leaving the locks of wool free

45 to move under the action of the bath and the sprays of said liquid and controlling the rate of movement of the wool through said bath, by regulating the pressure of the spray used in propelling it, the wool floating freely except as the action of said sprays may momentarily submerge it.

4. That improvement in methods of scouring

50 wool, comprising the steps of floating the wool in a bath of scouring liquid under such conditions that the dirt can settle freely out of the upper part of said bath propelling the wool through said bath by directing a series of well-dispersed

55 sprays of such scouring liquid against it from a series of points above the surface of said bath and at such an angle as to force the wool in the desired direction and to subject the wool to a scouring action, the wool floating freely except as the action of said sprays may momentarily submerge it, and controlling the rate of move-

60 ment of the wool through said bath by adjusting the angles at which the sprays strike the wool.

5. A wool scouring apparatus for scouring wool and simultaneously floating the wool in a bath under such conditions that the dirt can freely settle out of said bath, comprising a scouring bowl

65 adapted to hold a bath of scouring liquid, means for maintaining said liquid at approximately a predetermined level in said bowl, a screen extending approximately across the bowl where it forms a false bottom positioned beneath the level of

said liquid as maintained by said liquid level maintaining means to permit substantially all the wool to float above and out of contact with said screen, dirt collecting means located beneath said false bottom, said bowl having substantially parallel sides above said screen extending lengthwise of said bowl whereby the wool locks may float freely through most of the length of said bowl without increasing or diminishing the confinement by the sides of said bowl, means for subjecting the wool to a scouring action but permitting free floating except as the action of said means may momentarily submerge the wool and for propelling the wool lengthwise of said bowl, the last mentioned means comprising a plurality of series of spray nozzles, each series extending transversely across said bowl and the different series being spaced from each other lengthwise of the bowl, means mounting each of said series of spray nozzles above the level of the liquid as maintained by said liquid level maintaining means, said nozzles being directed so as to cause the wool locks to move longitudinally of said bowl and forming the sole means for causing said wool to move from substantially one end to nearly the other end of said bowl, said nozzles including means for causing the sprays to be broken up into well-dispersed form, whereby substantially all of the wool locks will be scoured and moved thereby substantially from one end nearly to the other end of said bowl without being submerged except as above stated, whereby it may float out of contact with said false bottom thereby preventing impedance of its movement by said false bottom.

6. A wool scouring apparatus for scouring wool and simultaneously floating the wool in a bath under such conditions that the dirt can freely settle out of said bath, comprising a scouring bowl adapted to hold a bath of scouring liquid, means for maintaining said liquid at approximately a predetermined level in said bowl, a screen having a surface which is spaced substantially uniformly below the level of the liquid in the bowl forming a false bottom positioned beneath the level of said liquid as maintained by said liquid level maintaining means to permit substantially all the wool to float above and out of contact with said screen, dirt collecting means located beneath said false bottom, said bowl having substantially parallel sides above said screen extending lengthwise of said bowl whereby the wool locks may float freely through most of the length of said bowl without increasing or diminishing the confinement by the sides of said bowl, means for subjecting the wool to a scouring action but permitting free floating except as the action of said means may momentarily submerge the wool and for propelling the wool lengthwise of said bowl, the last mentioned means comprising a plurality of series of spray nozzles, each series extending transversely across said bowl and being spaced from each other lengthwise of the bowl, means mounting each of said series of spray nozzles above the level of the liquid as maintained by said liquid level maintaining means, said nozzles being directed so as to cause the wool locks to move longitudinally of said bowl and forming the sole means for causing said wool to move from substantially one end to nearly the other end of said bowl, said nozzles including means for causing the sprays to be broken up into well-dispersed form, whereby substantially all of the wool locks will be scoured and moved thereby substantially from one end

nearly to the other end of said bowl without being submerged except as above stated, whereby it may float out of contact with said false bottom thereby preventing impedance of its movement by said false bottom.

- 5 7. A wool scouring apparatus for scouring wool and simultaneously floating the wool in a bath under such conditions that the dirt can freely settle out of said bath, comprising a scouring bowl 10 adapted to hold a bath of scouring liquid, means for maintaining said liquid at approximately a predetermined level in said bowl, a screen extending approximately across the bowl where it forms a false bottom positioned beneath the level of said 15 liquid as maintained by said liquid level maintaining means to permit substantially all the wool to float above and out of contact with said screen, dirt collecting means located beneath said false bottom, said bowl having substantially parallel 20 sides above said screen extending lengthwise of said bowl whereby the wool locks may float freely through most of the length of said bowl without increasing or diminishing the confinement by the sides of said bowl, means for subjecting the wool 25 to a scouring action but permitting free floating except as the action of said means may momentarily submerge the wool and for propelling the wool lengthwise of said bowl, the last mentioned means comprising a plurality of series of spray 30 nozzles, each series extending transversely across said bowl and the different series being spaced from each other lengthwise of the bowl, means mounting each of said series of spray nozzles above the level of the liquid as maintained by said 35 liquid level maintaining means, said nozzles being directed so as to cause the wool locks to move longitudinally of said bowl and forming the sole means for causing said wool to move from substantially one end to nearly the other end of said 40 bowl, said nozzles including means for causing the sprays to be broken up into well-dispersed form, whereby substantially all of the wool locks will be scoured and moved thereby substantially from one end nearly to the other end of said bowl without being submerged except as above stated, whereby it may float out of contact with said false bottom thereby preventing impedance of its movement by said 45 false bottom, and mechanical means at the delivery end of the bowl for taking the wool out of the bowl and for delivering the same to 50 additional apparatus.
